UNITED STATES PATENT OFFICE.

EDWARD ROOS, OF CHICAGO, ILLINOIS.

DESIGN FOR A CURTAIN-POLE BRACKET.

SPECIFICATION forming part of Design No. 27,915, dated November 30, 1897.

Application filed October 14, 1897. Serial No. 655,224. Term of patent 7 years.

To all whom it may concern:

Be it known that I, EDWARD ROOS, a citizen of the United States, residing at Chicago, in the county of Cook and State of Illinois, 5 have invented and produced a new and original Design or Useful Shape for Curtain-Pole Brackets, of which the following, in connection with the accompanying drawings, is a full, clear, and exact specification.

10 In the said drawings, Figure 1 is a perspective view of a curtain-pole bracket embodying my design, and Fig. 2 is a front or end view thereof on a larger scale.

The essential features of my design consist 15 of a curtain-pole bracket having the knob-like portion A, provided on one side with the cavity B, the rosette C, and the stem D.

The knob A is spherical, but flattened on the side opposite the stem D and there given 20 the form of a rosette C, consisting of a central figure E, composed of radially-arranged leaves surrounded by a wreath F. From the side of the spherical portion A opposite the

cavity B projects a pinnacle-like ornament composed of a globular portion G, a narrow 25 neck g at one side, and an attenuated part or point g' at the other side, a bead g'' being located at a point between the neck g and the side of the spherical portion A.

The stem D projects from the spherical 30 portion A at the side opposite the rosette C. The base of the stem is enlarged, as shown at d, while at a point intermediate of the sphere A and base d is a pair of beads or rings d'.

Having thus described my invention, what I claim as new therein, and desire to secure by Letters Patent, is—

The new and original design or useful shape 40 for a curtain-pole bracket substantially as herein shown and described.

EDWARD ROOS.
